APPARATUS FOR DEVELOPING AND FIXING
PHOTORESITIVE ELEMENTSGeorge C. Kalbfleisch and Andrew P. Keller,
Tiffin, Ohio

Application March 31, 1932, Serial No. 602,216

7 Claims. (Cl. 95—96)

This invention relates to maintaining temperature in a chamber.

This invention has utility when incorporated in developing and fixing films or plates, especially in 5 photographic operations.

Referring to the drawings:

Fig. 1 is a front elevation, with parts broken away of an embodiment of the invention;

Fig. 2 is a plan view of features of the piping 10 and portions of the structure;

Fig. 3 is a detail view of the waste piping;

Fig. 4 is a rear elevation with parts broken away;

Fig. 5 is a section on the line V—V, Fig. 4;

15 Fig. 6 is a section on the line VI—VI, Fig. 4;

Fig. 7 is a section on the line VII—VII, Fig. 4, and

Fig. 8 is a wiring diagram of the electric features of control.

20 Frame 1 has vibration take-up bracket 2 for deck 3 (Fig. 6) carrying electric motor 4 for operating refrigeration unit including compressor or pump 5 for a cooling medium circuit having delivery duct 6 and return duct 7.

25 The frame 1 above the refrigerator unit is provided with cabinet section 8 enclosing heat insulation 9 as a jacket for tank 10. This heat insulation 9 is desirably of a character not to sour or sweat. Rock wool base insulation has been found 30 satisfactory. The chamber 10 in its extent has downwardly therein short of its bottom, intermediate partition walls 11, 12, having insulation jacket filler 13 (Fig. 2) which is desirably of insulation similar to the insulation 9. This insulation 13 houses vessel 14 as an intermediate overflow chamber extending with its jacket short of the bottom of the chamber 10 to leave passage 35 (Fig. 6) between developing chamber 16 and fixing chamber 17 of this photographic accessory 40 tank cabinet.

Line 6 from the refrigerator unit extends upwardly through the jacket about the tank 10 into the bottom of fixing chamber 17 where it is connected to duct 18 (Fig. 2) having branch 19 to the 45 upper part of coil 20 about the inner side of this chamber 17 near the top. Brackets 21 anchor the wraps of this coil 20 with the side walls 10, 12, of this chamber 17. This coil 20 descending from the upper portion of the chamber 17 has duct 22 50 through the crossover portion 15 to duct 23 in communication through the bottom of the chamber 16 with return duct 7 to the refrigerator unit. The duct 18, besides the branch 19, has branch 24 extending through the crossover portion 15 between the chambers 16, 17, thence upward to the

top portion of coil 25 about developing chamber 16 similar to the coil 20. It is desired to maintain the chambers 16, 17 at approximately the same temperature and of approximately the same capacity. However, as the riser 6 enters the 60 chamber 17, it has been found in an instance of practice that two more wraps for the coil 25 than the coil 20 effectively balances the chilling for the two chambers. This coil 25 is anchored to the walls 10, 11, by brackets 21 similar to the brackets 65 21. From this upper portion of the chamber 16 the downward wraps of this cooling coil 25 have duct 26 therefrom to the branch fitting 23. The developing chamber 16 and the fixing chamber 17 are thus in parallel in their connection to the 70 cooling unit.

The wall 11 is provided with openings 27 to pocket 28 (Figs. 2, 7) extending downward along the wall 11 and thus in communication with the chamber 16 but spaced slightly outward from the coil 25. In the pocket 28 is thrust stem 29 of thermometer 30 (Fig. 1) thereby serving as a visual indicator for the condition of water 31 in the chambers 16, 17, having the intercommunicating portion 15.

In practice a constant temperature is one insuring uniformity for the output in developing and fixing operations. With certain photographic sensitive coatings desirable results are obtained today by holding the developing and 85 fixing temperature at 65° F.

The rear of the chamber 16 has removable section 32 through which connections may be made for locating a flat tube 33 (Figs. 2, 7) in the chamber 16 against the coils 20. This tube 33 contains 90 a temperature responsive expandible medium. The section 32 seals connection at the chamber 16 for the tube 33 against leakage of water 31. The cabinet has this portion closed in by removable plate 34. From this tube 33 there extends flexible duct 35 to electric switch 36 (Fig. 1). Upon the expansion of this medium in the tube 33 in any state above a set temperature for the switch 36 of say 65° F., the switch 36 will close. The electric power connection by plug at electric fitting 37 (Fig. 5), below the cabinet and at the end thereof remote from the unit, may serve for a power supply. The wiring from this fitting 37 may be to outlet box 38 to fuse 39 thence by conduit 40 to the switch 36 with conduit 41 therefrom 100 to the motor 4. When the temperature in the tank 10 falls below the point for temperature maintenance, say 65° F., the switch 36 automatically opens and the refrigerator unit 5 is stopped. Reversal of flow is precluded by check valve 42 in 110

this line 6 at insulation packed chamber 43 below the chamber 17.

The rear of the cabinet may be provided with hose connection 44 (Fig. 4) for a water supply to 5 pipes 45, 46. The pipe 46 extends to valve 47 which as opened, allows flow of water from pipe 48 into the chamber 17 below the coil 20 where it is downwardly directed by fitting 49. Due to the connection 15, the charging of the chamber 17 10 automatically fills or charges the chamber 16 to a similar extent.

The chambers 16, 17, have in the upper portions thereof ledges 50 upon which may rest outwardly extending flanges 51 (Fig. 1) of tanks 52 of chemically resistant material, say rubber, which may be used for the developing solution in tank 16 and for the fixing solution in the tank 17. These tanks 52 in the chambers 16, 17, extend into the water 31 and have such water serve as a temperature 20 controlled liquid jacket about the tanks proper 52 containing the chemical for developing as to the tank 16 and for fixing as to the tank 17. This facilitates the handling of this work. If the sensitive coated material be in strip film form, it may 25 be hung over bars or racks.

If the material be on glass plates or film sections such may be inserted in perforate channel U-frame 53 and then locked by perforate channel bar 54 locked into holding position. The frame 30 has cross bar 55 rest on shoulder 56 near the top of the rubber tank 52 for suspending the sensitive coated base of glass or film in the chemical solution.

In the lower portion of the tank 17 is waste outlet 56 (Fig. 3) having screw thread riser sleeve 57 into which may be inserted plug 58. For normal draining of this tank 10, removal of the plug 58 leaves a depth of water to submerge metal jacket 59 for electric heater unit 60. Beneath the coil 40 in the chamber 17 there is located a temperature responsive tube 61 (Fig. 5) similar to the tube 33 and similarly mounted. However, the purpose thereof is opposite to that of the tube 33, for this tube 61 is connected up for raising the temperature of the bath instead of lowering. To this end flexible duct 62 from the tube 61 extends to switch 63, similar to the switch 36.

From the electric current supply past fuse 64 from the outlet box 39 there is conduit 65 to the switch 63 having conduit 66 extending therefrom to the electric heater unit or resistance 60 in the chamber 59 in the crossover region 15 between the chambers 16, 17. As the temperature becomes too low, the switch 63 is effective for cutting in the 55 electric current for the resistance 60 in warming the jacket or the shell 69. The heat thus generated has thermosiphon action for creating upward circulation from the cross-over 15 in parallel for the chambers 16, 17, to bring the temperature 60 thereof up to the point at which it is desired to have it maintained, as 65° F. When such point is reached, the switch 63 automatically cuts out the heater 60. The refrigerator unit 5 and the heater unit 59 thus cooperate for maintaining a 65 temperature constant in the water jacket tanks or chambers 16, 17, about the chemical carrying tanks 52.

If it be desired to drain fully the tank 10 it is necessary to remove the sleeve 57. The waste 70 flows from this outlet 56 (Fig. 3) by way of duct 67 to trap 68 having outlet 69 therefrom in the rear of the cabinet for, say a sewer connection.

It is desirable in the maintenance of constant 75 temperature for operation of the chemical baths, especially when not working therein, that there

be closure to hold the temperature against radiation departure by dissipation from or into the surrounding atmosphere. To this end insulation blocks 70 (Fig. 1) may be used at closures for 80 openings 71 at the tops of the tank portions 16, 17, thereby closing the chamber sections as well as the tanks 52.

This leaves intermediate overflow chamber 14 in which is located rinsing chamber provided with 85 ledge 73 near its upper portion upon which the termini of the bars 55 may rest in suspending the chemically treated film or plate for rinsing action in this tank 72. This rinsing may be effective by circulation of water. The pipe 45 extends to valve 74 which, as opened, allows water to flow by pipe 75 to pipe 76 along the bottom of the tank 72 (Fig. 6). This pipe 76 has, downwardly directed along opposite sides thereof, jet openings 77 thereby distributing the incoming water, which as rising may overflow through annular series of 90 openings 78 into jacket chamber 79 between the chambers 14, 72. This communicates with down pipe 80 as a branch to waste 67.

The circulation in this rinsing chamber is positive due to the external water supply. The holding of temperature herein is not maintained. As to the fixing and developing baths a temperature constant is maintained and the circulation may be due entirely to the thermo-siphon action. However, such latter circulation may be supplemented herein by a positive flow promotion. To 100 this end motor bracket 81 (Fig. 6) may be mounted upon the platform 3 to carry motor 82 directly connected to rotary pump 83. Switch 84 (Fig. 5) near the fitting 37 may be thrown so 105 that electric current through conduit 85 to the motor 82 may operate pump 83 which has water supply connection from the tank 17 by riser duct 86 (Fig. 1) from near the bottom of the tank upward through the insulation 9 and outward by 110 fitting 87 and duct 88. Duct 89 from the pump extends to fitting 90 adjacent to fitting 87 for spilling directly into upper portion of the tank 7.

In the event it be desired to spill into the tank 16 or to have circulation in an intermediate or 115 other vessel, a break in the delivery hose 89 or a connection for such purpose may be made.

The cabinet is a unit which may be assembled in a housing equipped with enamel panels 91 and provided with feet 92. It is compact and automatic in its operation thereby simplifying the 120 photographer's work in producing a uniform high quality of output even for positives as well as negatives.

By pulling plug 93, the rinsing tank 72 may be 125 drained. The tanks 52 have chemical solutions 94, 95, therein.

Any overflow from the tanks 16, 17, is by duct 96 into the jacket chamber 79.

What is claimed and it is desired to secure by 130 Letters Patent is:

1. A photographic accessory comprising a multiple intercommunicating chamber bath cabinet, different cooling coils for the respective chambers, insulation walls between the chambers, and automatic temperature control cut-in means for rendering the coils effective. 140

2. A photographic accessory comprising a multiple intercommunicating chamber bath cabinet, cooling coils for the respective chamber upper 145 portions in parallel, insulation walls between the chambers and a heater for the chamber lower portions in parallel.

3. A photographic accessory comprising a multiple intercommunicating chamber bath cabinet, 150

cooling coils for the respective chamber upper portions in parallel, insulation walls between the chambers, a heater for the chamber lower portions in parallel, and automatic cut-in mechanism for the coils and heater.

4. A photographic bath cabinet comprising a pair of intercommunicating chambers, temperature control means including jacket-providing insulation walls for the chambers, and a rinsing tank between the insulation walls of the respective chambers.

5. A photographic bath cabinet comprising a

rinsing tank, and downwardly directed distributed-flow circulation-effecting means therefor.

6. A photographic bath cabinet comprising a rinsing tank, a downwardly directed jet along the bottom within said tank for water supply, an annular series of outlet ports near the top of and from said tank for overflow, and a common passage from said ports for receiving the overflow.

7. A photographic bath cabinet having a plurality of chambers and a common overflow receiver in the cabinet for said chambers.
